UNITED STATES PATENT OFFICE.

HARRY E. GLADISH, OF HIGGINSVILLE, MISSOURI.

MOTOR CHAIR.

Application filed February 27, 1922. Serial No. 539,535.

To all whom it may concern:

Be it known that I, HARRY E. GLADISH, a citizen of the United States, residing at Higginsville, in the county of Lafayette and State of Missouri, have invented new and useful Improvements in Motor Chairs, of which the following is a specification.

The object of my said invention is the provision of a simple, comfortable easily controlled and easily steered motor chair designed more especially for the use of invalids and convalescents.

To the attainment of the foregoing, the invention consists in the improvement as hereinafter described and definitely claimed.

In the accompanying drawings, forming part of this specification:—

Figure 1 is a side elevation of the motor chair constituting the best practical embodiment of my invention that I have as yet devised.

Figure 2 is a rear elevation of the same.

Figure 3 is a front elevation of the chair.

Figure 4 is a horizontal section through the chair on the line 4—4 of Figure 1.

Figure 5 is a detail horizontal section on the line 5—5 of Figure 1.

Figure 6 is a detail fragmentary plan, partly in section, showing the driving connection.

Figure 7 is an enlarged view illustrative of the one-hand control.

Figure 8 is a section on line 8—8 of Figure 4, showing the brake drum and band.

Similar numerals of reference designate corresponding parts in all of the views of the drawings.

The chair body may be of any appropriate construction though I prefer to have it comprise a seat 1, a back 2, side arms 3, adjustment straps 4, and a foot rest 5. The rear portion of the seat 1 is superimposed upon and connected to a bolster 6, Figure 2, and the said bolster, in turn, is superimposed upon and connected to longitudinal elliptical springs 7, arranged in parallel. A rear axle housing 8 supports the springs 7 and contains axle sections 9 and an equalizing gearing 10, Figure 6; the said axle sections 9 being equipped in conventional manner with drive wheels 11.

Appropriately connected to and extending forwardly from the housing 8 is the frame 12 of the chair which frame is provided at its forward end with a cross bar 13 to which

are pivotally connected knuckles 14, Figures 3 and 4, bearing forward, steering wheels 15. The said cross-bar 13 is disposed in a horizontal plane considerably below that of the major horizontal portion of the frame 12 and is joined to the said major portion by forward corner uprights 16 which serve through the medium of cushioning springs 17 to support rods 18 pendent from the forward corners of the seat 1, the rods 18 being guided in lateral projections 19 on the uprights 16, and the springs 17 being interposed between the lower projections 19 and nuts 20 or other enlargements on the rods 18, Figure 3.

It will be apparent from the foregoing that the chair body is adequately cushioned at the back and front with a view to preventing the transmission of shocks and jars to the occupant and operator of the chair.

Carried on cross-bars 21 comprised in the horizontal portion of the frame 12 is an electric motor 22, the armature shaft 23 of which is connected through a universal joint 24 with the shaft 25 in connection with the equalizing gearing 10.

Mounted on a platform 26 on the forward portion of the frame 12 is a box or casing 27 in which is a storage battery 28.

At 29 is a hollow post fixed to the frame 12 and clipped at 29* or otherwise held to the seat 1 of the body in such manner as to permit the body to move up and down relative to the post, and at 30 is a tube carried by said post 29. Extending through the post 29 is a steering-shaft 31 on the lower exposed end of which is a crank 32, connected through a rod 33 with the cross-bar 34 interposed between and connecting the rearwardly-directed arms of the knuckles 14. Arranged at and adapted to be turned on the upper end of the post 29 is a handle 35 that is fixed to and is adapted to turn the shaft 31 about its axis for the steering of the chair.

For the braking of the chair I provide the hand lever 36 fulcrumed at 37 on the post 29, and I also provide drums 38 fixed to the wheels 11, bands 39 about said drums and connected at 40 to the housing 8, a transverse rack shaft 41, journaled in bearings 42 on the housing 8 and having arms 43 connected to the bands 39 and also having a crank 44, and a Boden wire or other suitable flexible connection 45 between the crank 44 and the post 29.

and the hand lever 36. Manifestly when the hand lever 36 is moved toward the handle 35 the brake bands 39 will be applied to retard the chair while when the said lever 36 is released the resiliency of the bands 39 will release the same from their complementary drums 38. Only slight swinging movement of the handle 35 is necessary for the proper steering of the chair, and, therefore, the chair occupant is always able with the band used for steering to take hold of and raise the lever 36 and thereby efficiently brake the chair.

The handle 35 is chambered as designated by 50 in Figure 7, and in the said chamber 50 are terminals 51 and 52, arranged in a normally open electric circuit with the motor 22 and the storage battery 28. Fitted crumpled on the terminal 51 is a lever-like conductive switch blade 53, movable into and out of contact with the terminal 52, and pivotally connected to the ends of the said blade 53 and extending loosely through guide apertures in the upper wall 54 of the chamber 50 are finger pieces 55 and 56, preferably dielectric in character. It will be readily apparent that when the occupant and operator of the car desires to stop the propulsion of the same it is simply necessary for him or her to depress the finger piece 55 when the electric circuit and the functioning of the motor 22 will be interrupted. To start the chair it is merely necessary for the occupant and operator to depress the finger piece 56 so as to make contact between the blade 53 and the terminal 50 when the complete circuit will be re-established and the wheels 11 will be driven by the motor 22.

40 It will be observed that I have shown the control of the chair in position for operation by the right hand of the chair occupant. Obviously, however, it is within the purview of my invention to locate the 45 control for left hand operation, and in this connection I would have it understood that I prefer to so connect the post 29 that it can be readily transferred or shifted from the right hand side of the chair body to the 50 left-hand side thereof, and I also prefer to provide the rod 34 with an auxiliary connection 34^a, Figure 5, for the rod 33, and to provide the rock-shaft 41 with an auxiliary crank for the connection of the wire 45.

55 I have entered into a detailed description of the construction and relative arrangement of the parts embraced in the present and preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may

be made such as fall within the scope of my invention as defined in my appended claims.

Having described my invention, what I claim and desire to secure by Letters-Patent, 70 is:—

1. A motor chair comprising an axle housing, a frame connected to and extending said housing and having uprights at its forward corners, a cross-bar carried at the lower ends of said uprights, knuckles pivotally connected to said cross-bar and bearing steering wheels, axle sections in the housing and bearing drive wheels, an electric motor and a storage battery carried on said frame, a connection between the armature shaft of the motor and the axle sections and including equalizing gearing in the housing, a body spring-supported on the corner uprights of the frame and the housing, and a one-hand control carried by the frame and including means to swing the steering wheels and means to establish and interrupt an electric circuit including the storage battery and the motor. 90

2. A motor chair comprising an axle housing, a frame connected to and extending said housing and having uprights at its forward corners, a cross-bar carried at the lower ends of said uprights, knuckles pivotally connected to said cross-bar and bearing steering wheels, axle sections in the housing and bearing drive wheels, an electric motor and a storage battery carried on said frame, a connection between the armature shaft of the motor and the axle sections and including equalizing gearing in the housing, a body spring-supported on the corner uprights of the frame and the housing, means to brake the chair, and a one-hand control carried by the frame and including means to swing the steering wheels, means to apply the brake means, and means to establish and interrupt an electric circuit including the storage battery and the motor. 100

3. A motor chair comprising an axle housing, a frame connected to and extending said housing and having uprights at its forward corners, a cross-bar carried at the lower ends of said uprights, knuckles pivotally connected to said cross-bar and bearing steering wheels, axle sections in the housing and bearing drive wheels, an electric motor and a storage battery carried on said frame, a connection between the armature shaft of the motor and the axle sections and including equalizing gearing in the housing, a body spring-supported on the corner uprights of the frame and the housing, means to brake the chair, and a one-hand control carried by the frame and including means to swing the steering wheels, means to apply the brake means, and means to establish and interrupt an electric circuit including the storage battery and the motor; the forward 110

115

120

125

130

corner uprights of the frame each having lateral apertured projections, and the body having forward pendent rods guided in said projections and provided between the same 5 with enlargements, and the forward spring support being formed by springs on said rods and between the lower projections and the rod enlargements.

4. A motor chair comprising an axle 10 housing, a frame connected to and extending said housing and having uprights at its forward corners, a cross-bar carried at the lower ends of said uprights, knuckles pivotally connected to said cross-bar and bearing 15 steering wheels, axle sections in the housing and bearing drive wheels, an electric motor and a storage battery carried on said frame, a connection between the armature shaft of the motor and the axle sections and 20 including equalizing gearing in the housing, a body spring-supported on the corner uprights of the frame and the housing, means to brake the chair, and a one-hand control carried by the frame and including 25 means to swing the steering wheels, means to apply the brake means, and means to establish and interrupt an electric circuit including the storage battery and the motor; the said means to swing the steering means

being in the form of a cranked rock shaft 30 in a hollow post and with a handle at the upper end thereof, the brake applying means being in the form of a hand lever fulcrumed on said post, and the means to establish and interrupt the electric circuit being in the 35 form of terminals in a chamber of the handle, a conductive blade fulcrumed on one terminal and movable into and out of contact with the other terminal, and finger pieces connected to said blade and movable 40 in a wall of the chamber.

5. In a one-hand control, the combination of a hollow post, a tube carried by and alongside said post, a rock shaft in the post and having a chambered handle, a hand lever 45 fulcrumed on the post in close proximity to the handle, a flexible connection on said lever and extending through said tube, terminals in the chamber of the handle, a conductive blade in said chamber and fulcrumed on one 50 terminal and movable into and out of contact with the other terminal, and finger pieces on said blade and guided in apertures in a chamber wall.

In testimony whereof, I affix my signature.

HARRY E. GLADISH.
